UNITED STATES PATENT OFFICE.

WARREN LEWIS, OF COUTOLENC, CALIFORNIA.

BED-COVER AND AUTOMOBILE-ROBE HOLDER.

1,109,432.

Specification of Letters Patent. Patented Sept. 1, 1914.

Application filed July 11, 1913. Serial No. 778,609.

To all whom it may concern:

Be it known that I, WARREN LEWIS, a citizen of the United States, residing at Coutolenc, in the county of Butte and State of California, have invented certain new and useful Improvements in Bed-Cover and Automobile-Robe Holders; and I do hereby declare the following to be a full, clear, and exact description of the invention, such as will enable others skilled in the art to which it appertains to make and use the same.

This invention relates to new and useful improvements in resilient or yieldable holding devices for bed clothes, lap robes, or similar coverings, and as its principal object contemplates the provision of a device of this character which, when attached to the bed clothes or covering, may be stretched to prevent them from being thrown aside, or pushed off, as a result of the restive movements of the user while asleep.

A further and more specific object is to provide a device which will not require any particular fastening devices for its application to the covering, and will not impair the value of the article to which it is applied, as is usually the result of the employment of safety pins, toothed clamps, and the like.

The above and additional objects are accomplished by such means as are illustrated in the accompanying drawings, described in the following specification and then more particularly pointed out in the claims which are appended hereto and form a part of this application.

With reference to the drawings, wherein I have illustrated the preferred embodiment of my invention as it is reduced to practice, and throughout the several views of which similar reference numerals designate corresponding parts: Figure 1 is a transverse section taken through a bed, illustrating the bed clothes holder in assembled position; Fig. 2 is a top plan view.

Proceeding now to the description of the drawings, the numerals 1 and 2 designate the side boards of a bed, while the numeral 3 designates the bed clothing.

The preferred embodiment of this invention consists essentially in an elastic strap 4, provided with an adjusting buckle 5, a snap hook 6, and attaching rings 7, 8 and 9. The adjusting buckle 5 is of the usual type and is designed to permit the adjustment of the length of the strap. The snap hook

6 is also of the common type, and is secured to the looped portion 10 formed by looping one terminal of the strap to permit the application of the member 5. The other terminal of the strap is looped, as at 11, and in this loop are secured the rings 8 and 9, the ring 8 being adapted for co-operation with the snap hook 6, and the ring 9 being designed to receive a cord or similar fastening device 12, which is tied around the side board 1 of the bed. The ring 7 is secured by a similar cord 13 to the side board 2.

In practice the rings 7 and 9 are secured to the side boards by the cords 12 and 13, and the bed covering is placed on the lower strand of the strap 4. The upper strand of the strap 4, which carries the snap hook 6, is then placed on top of the bed covering and is connected to the ring 8. By manipulation of the member 5, the gripping engagement exerted by the upper and lower strands of the strap 4 upon the covering 3 may be varied, as desired.

As regards the particular advantages resultant from the novel form of structure employed in this invention, it is to be noted that the covers are in no way marred in appearance, or impaired as regards their value, by any permanent incision or the like, such as is usually made by safety pins, toothed clamps, and similar fastening devices which are often employed in securing the bed clothing against displacement. It is also to be observed that by employing an elastic strap 90 the restive movements of the sleeper are not resisted to such an extent as would render sleep uncomfortable.

In reduction to practice, I have found that the form of my invention, illustrated in the drawings and referred to in the above description, as the preferred embodiment, is the most efficient and practical; yet, realizing that the conditions concurrent with the adoption of my device will necessarily vary, I desire to emphasize the fact that various minor changes in details of construction, proportion, and arrangement of parts may be resorted to, when required, without sacrificing any of the advantages of my invention, as defined in the appended claims.

What is claimed is:

1. A holder for covering comprising an elastic strap adapted to surround the covering, a ring carried intermediate the end of the strap, a pair of rings secured to one of the ends of said strap, a snap hook carried

on the other end of said strap and adapted to engage one of said last named rings, and flexible tie cords carried by the first named and the other of the last named rings.

5. 2. A holder for covering comprising an elastic strap adapted to surround the covering, a ring carried intermediate the end of the strap, a flexible tie cord carried by said ring, a pair of rings secured to one of the 10 ends of the strap, a snap hook, the other end of said strap being looped through the snap hook, an adjusting buckle on said strap ad-

jacent the last named end thereof and secured to the last named end and a flexible tie cord carried by one of last named rings, 15 the other of said last named rings being adapted for engagement with the snap hook.

In testimony whereof I affix my signature in presence of two witnesses.

WARREN LEWIS.
